DESIGN FOR A DRAWER PULL

Henry L. Pehrson, Rockford, Ill., assignor to
Anderson Brass Shops, Inc., Rockford, Ill., a
corporation of Illinois

Application December 6, 1937, Serial No. 73,387

Term of patent 3½ years

To all whom it may concern:

Be it known that I, Henry L. Pehrson, a citizen
of the United States, residing at Rockford, in the
county of Winnebago and State of Illinois, have
invented a new, original, and ornamental Design
for a Drawer Pull, of which the following is a
specification, reference being had to the accom-
panying drawing forming part thereof.

In the drawing, Figure 1 is a plan view of a
drawer pull of my new design.

Fig. 2 is a side elevation.

Fig. 3 is a section taken along the line 3—3
of Fig. 1.

The design is especially characterized by hav-
ing two straight parallel bars projecting into the
sides of and supported at opposite ends by posts
of contrasting color.

I claim:

The ornamental design for a drawer pull, sub-
stantially as shown.

HENRY L. PEHRSON.
